UNITED STATES PATENT OFFICE.

WILLIAM E. WINE, OF TOLEDO, OHIO.

CAR-DOOR CONSTRUCTION.

Application filed March 5, 1923. Serial No. 622,852.

This invention relates to door spreader construction for railway cars and has for its principal object to provide an improved form of spreader, whereby a pair of doors may be held in a definite spaced relationship and caused to operate as a single door.

Another object is to provide an improved door-stiffening member in the form of a flanged beam.

10 A still further object is to provide a door-supporting member having a projecting end arranged at an angle best suited for cooperation with other portions of the door-supporting mechanism.

15 A still further object is to provide a preferred form of door spreader, particularly adapted for use with doors having marginal flanges outstanding from the face of the door.

With such objects and others in view, the 20 invention consists of the construction, combination and arrangement of parts as will be herein described and particularly claimed.

In the accompanying drawings, which show a preferred form of the invention:

25 Figure 1 is a plan view of the door spreader constructed in accordance with my invention, the spreader being shown as attached to a pair of flanged hopper doors.

Figure 2 is a fragmentary end elevational 30 view of the doors and the door spreader.

Figure 3 is an enlarged fragmentary plan view of one end of the door spreader, showing in dotted lines a door-supporting member cooperating therewith.

35 Figures, 4, 5 and 6 are transverse vertical sectional views of the door spreader, these views being taken on the lines 4—4, 5—5 and 6—6, respectively, of Figure 1.

Referring to the drawings, the door spreader, indicated by the numeral 1, is preferably 40 formed from a steel plate which is forged, pressed or shaped to provide certain edges thereof with marginal flanges. The spreader is particularly adapted for use with a pair of hinged doors, such as 2 and 3, which are 45 preferably secured to the spreader by means of rivets 4. The doors may conveniently be provided with outstanding flanges, such as 5, along their edges and it is desirable that the 50 door spreader should extend continuously and uninterruptedly over the flanges. The door contacting edge of the spreader is provided with a continuous marginal flange 6, a portion 7 thereof being arranged in the plane of

the outer faces of the doors and adapted to 55 contact the said faces. The intermediate portion of the spreader is preferably offset from the plane of the door faces to provide a space for the innermost flanges 5 of the said doors but the marginal door contacting flange of the 60 spreader preferably extends continuously and uninterruptedly around this offset portion, as at 8. Prior to being formed with marginal flanges the maximum width of the plate from which the spreader 1 is fashioned, is intermediate the ends of the spreader, as clearly shown by the dotted lines 9 in Figure 1. The flange 8 is of greater width therefore than the adjacent flanges 7 and this increase in width of the flange 8 compensates to a degree for the reduced depth of the spreader at this reduction in depth or intermediate portion. To further compensate for this offset 65 the opposite edge of the spreader is arched or formed in a cambered line. As the lower 70 dotted line 9 in Figure 1 indicates the preferable contour of the plate prior to the formation of the lower flanges 10 and 11 it will be apparent that a greater amount of material 75 is available for forming the intermediate portions of the flange 10 than is available for forming the outer portions 11 of the said flange so that, as indicated in Figure 6, the 80 central portion of the flange 10 is of considerably greater width or height than the portions 85 11 thereof toward the end of the spreader. In fact, in the preferable construction of the spreader, as herein shown, the marginal flanges 11 are reduced in height so as to merge 90 into the web of the said spreader adjacent the 95 ends, as shown at 12.

Such spreaders are frequently used with 100 cars of the twin hopper type, such as illustrated in my Patent No. 1,486,210, issued March 11, 1924. When door-supporting 95 members, such as the well known form of pivoted hook disclosed in said patent and herein indicated at 13, are disposed at an angle to agree with the acute planes of the respectively adjacent hopper side sheets, their surfaces 100 of engagement with the portions of the door spreader which constitute door-supporting arms are at an acute angle with the plane of the door and at an acute angle with the general direction of the door spreader. In order that a proper contact may be had between the hook 13 and the end of the spreader, I arrange the portions 14 of the flange 6 of the 105

spreader at an acute angle with the door-contacting portions thereof. When used with such hooks these portions 14 of the flanges lie normal to the plane of the hooks, so that 5 the hook may engage the flange in a true manner. This angular direction of the hook seat portions of the door spreader also tends to prevent the hook creeping outward toward the ends of the spreader. As an additional 10 safe-guard against the hooks creeping off the ends of the spreader, an end flange 15 may be provided at each end of the spreader to serve as a positive hook stop.

I have thus provided an improved form of 15 door spreader which may be formed in an economical manner and be applied to doors of the type described without cutting away any portion of the door flanges. In prior constructions it has been necessary either to cut 20 the door flanges to allow for the extension of the spreader or to substitute for a spreader having integral hook-engaging portions a built-up structure having separable hook-engaging members. Both of these constructions 25 are avoided by the utilization of the spreader which is the subject of this invention. Considerable difficulty has hereto been experienced in obtaining a proper contact between the door hooks and the hook seats on 30 the door, and this difficulty is also overcome in the present construction.

I have thus described a preferred embodiment of my invention. Other embodiments are contemplated within the scope of the appended claims without departing from the 35 spirit thereof.

What is claimed is:

1. A car door mechanism including in combination with a door hinged to the car body, 40 a door-supporting member pivoted to the car body adjacent an edge of the door the plane of operation of the door supporting member being inclined to the vertical and an arm extending outwardly from the door and having a portion thereof formed as a seat adapted 45 for engagement by the said door-supporting member, said seat lying in a plane at an acute angle with the plane of the door and substantially normal to the plane of movement 50 of the door-supporting member.

2. A car door mechanism including in combination with a door hinged to the car body, a door-supporting member pivoted to the car body adjacent an edge of the door to swing 55 in a direction longitudinally of the car, and an arm extending outwardly from the door and having a portion thereof formed as a seat adapted for engagement by the said door-supporting member, said seat lying in a plane at 60 an acute angle with the horizontal axis of the door arm and with the car side but substantially at right angles to the plane of movement of the door-supporting member.

3. A car door mechanism including in combination with a door hinged to the car body, a

door-supporting member pivoted to the car body to swing in a direction longitudinally of the car, and an arm extending outwardly from the door and having a portion thereof formed as a seat adapted for engagement by the said door-supporting member, the said door-supporting member being arranged to lie when in engagement with the said arm in a plane at an acute angle with the plane of the door, and the seat portion of said arm being arranged normal to the plane of movement of the door-supporting member.

4. A stiffener for the doors of railway cars involving a flanged member adapted to be secured to the outer face of the door and having an end portion extending beyond an edge of the door, the said end portion having a face extending outwardly and downwardly away from the door forming an acute angle with the flanged member of the stiffener, said face constituting a seat to engage a door supporting member mounted on the car.

5. A stiffener for the doors of railway cars embodying a flanged member adapted to be secured to the outer face of the door and having an end portion adapted to extend beyond an edge of the door to form a door supporting means, the said end portion being provided with a flange lying in a plane at an acute angle with the horizontal axis of the main portion of said flanged member and adapted to form a seat for a door-supporting member.

6. In car door construction, a pair of doors hinged side by side to the car body and spaced somewhat from each other, and a door spreader secured to both doors adjacent the free edges of the same and arranged to hold the doors in spaced relation, said doors being provided with outstanding marginal flanges along their adjacent edges, and the spreader being provided with a continuous marginal flange arranged to lie against the outer faces of the door and being offset slightly away from the plane of said outer faces to clear the marginal flanges of the doors, the marginal flange of the spreader being of increased width along the offset portion thereof.

7. A door spreader embodying a flanged beam of plate-like cross-section, said beam having aligned door-contacting flanges along one of its edges and being provided on its opposite edge with a flange progressively increasing in depth from points respectively adjacent the outer edges of the doors to a point intermediate the said doors.

8. A door spreader embodying a flanged beam formed from a single sheet of metal, said beam having aligned door-contacting flanges along one of its edges with an offset therebetween, and being provided with portions progressively increasing in depth toward the center of the door spreader and terminating short of the offset.

9. A door spreader embodying a flanged beam of plate-like cross-section, said beam

having integral aligned door-contacting flanges along one of its edges with a flanged offset therebetween, and having a flanged cambered back, the flange of the offset being 5 of increased height.

10. In car door construction, a pair of doors hinged side by side to the car body and spaced somewhat from each other, and a door spreader secured to both doors adjacent their 10 free edges for holding said doors in spaced relation, said doors being provided with outstanding marginal flanges along their edges adjacent the sides of the car, and said spreader being flanged along one of its edges to 15 constitute faces for contacting said doors and seats adapted for engagement by door-supporting means carried by the car body, said seats projecting laterally outward beyond said marginal flanges and being spaced from 20 the plane of the said door-contacting faces.

11. In car door construction, a pair of doors hinged side by side to the car body and spaced somewhat from each other, and a door spreader secured to both doors adjacent their 25 free edges for holding said doors in spaced relation, said doors being provided with outstanding marginal flanges along their edges adjacent the sides of the car, and said spreader being continuously flanged 30 along one of its edges to constitute door-contacting portions and a plurality of seats adapted for engagement by door-supporting means carried by the car body, said seats being at the ends of said spreader and extending laterally outward beyond said marginal 35 flanges and being spaced from the plane of the said door-contacting portions.

12. A door spreader formed of a sheet of metal and provided with flanges extending 40 lengthwise of said spreader along the opposite edges thereof, the flange along one edge being offset at the ends of the spreader to form seats adapted for engagement with door-supporting means, and the flange along 45 the other edge terminating inwardly of the ends of the spreader.

13. In car door construction, a door hinged to the car body, a flanged member carried by said door and projecting laterally outward 50 beyond an edge of the latter, said member having flanges at its opposite edges, the flange along one edge having an offset portion forming a seat adapted for engagement with door-supporting means carried by the car body, 55 and the flange along the opposite edge ter-

minating inwardly of the outer end of said seat.

14. In car door construction, a door hinged to the car body, a flanged member carried by said door and projecting laterally outward beyond an edge of the latter, said member being flanged at its outer end and along its opposite edges, the flange along one of said edges being continuous with said end flange and having an offset portion inwardly 60 of said end flange forming a seat adapted for engagement with door-supporting means carried by the car body.

15. In car door construction, a door hinged to the car body, a flanged member carried 70 by said door and projecting laterally outward beyond an edge of the latter, said member being flanged at its outer end and along opposite edges, the flange along one of said edges being continuous with said end flange 75 and having an offset portion forming a seat adapted for engagement with door-supporting means carried by the car body, and the flange along the opposite edge terminating at its outer end in spaced relation to said end flange.

16. A door spreader formed of a sheet of metal and provided with flanges extending lengthwise of said spreader along the opposite edges thereof, one of said flanges affording door-contacting portions, and both of said flanges being of greatest width at a point intermediate the ends of the spreader.

17. A door spreader having portions increasing in depth from its ends toward the 90 center and provided with a flange extending lengthwise of said spreader on one edge thereof, the flange increasing in width as the first named portion increases in depth.

18. A door spreader of substantially channel shape formed from a substantially triangular sheet of metal and provided with a flange along one of its edges to constitute 95 door-contacting portions.

19. A door spreader having a body portion 100 and provided along one of its edges with door-contacting portions, and having along its opposite edge inclined portions and a horizontal portion intervening therebetween, the horizontal portion lying within the angle 105 formed by the intersection of planes normal to the body portion of the spreader and passing through the said inclined portions.

In testimony whereof I affix my signature.

WILLIAM E. WINE.
